JOINT CONSTRUCTION

Thomas Guthrie, Albany, Calif., and Gordon R. Evans, Collingswood, N. J., assignors to Allied Chemical & Dye Corporation, a corporation of New York

Application August 6, 1945, Serial No. 609,270

3 Claims. (Cl. 285—10)

1

This invention relates to construction of fluid-tight joints particularly adaptable for use in connection with communicating gas conduits.

In the practice of chemical processes involving the manufacture of gases and the handling of the same in conduits usually of relatively large cross-section, it is often desirable to provide a gastight joint in a gas line one section of which is movable with respect to another. As one practical example, in the production of hydrogen fluoride gas, fluorspar and sulfuric acid are reacted in a horizontal rotary furnace to form an HF gas which is discharged from one end of the furnace thru an outlet opening or short pipe section the periphery of which is axially aligned with the horizontal axis of the furnace and which rotates with the furnace shell. This outlet opening is connected by some kind of a joint to a stationary flue serving to conduct the gas stream to the subsequent gas purification and HF recovery stages of the process. While the rotating furnace outlet, and the stationary gas main are designed so as to be at least theoretically coaxial, it is well known that in actual operation these elements are almost always out of alignment to some greater or lesser extent. In the past, this circumstance has caused considerable difficulty in connection with the construction of leakproof joints between the rotating furnace and the fixed pipe. The usual packed gland type of joint has proved inadequate, particularly after the apparatus has been in use for some period of time. Tendency for gas leakage at the joint has been so pronounced that, particularly in the manufacture of noxious gases, it has been the practice almost universally to operate at least the gas generating portion of the system under negative pressure in order to prevent escape of harmful gases to the atmosphere and avoid injury to workmen. Since commercially available joint constructions of previous design have not been gas-proof, the result of negative pressure operation has been infiltration of air thru the connecting joint to such an extent as to dilute the gas stream as much as 50% by volume. This difficulty requires the use of gas purification and recovery apparatus substantially larger than would be needed if infiltration of air from the atmosphere could be avoided.

This invention aims to provide a construction which affords a gasproof seal between two apparatus elements, at least one of which is movable with respect to the other, even if such elements are substantially out of alignment during operation.

2

The invention, its objects and advantages will appear from the following description taken in connection with the accompanying drawings in which Fig. 1 shows partly in elevation and partly in section a preferred embodiment, and Fig. 2 shows a section on line 2—2 of Fig. 1.

The improvements of the invention are particularly adapted for use in situations in which one conduit section rotates and the other is stationary; both sections rotate but one rotates at a higher velocity than the other; and both sections rotate but in opposite directions.

To exemplify utility of one embodiment of the invention, Fig. 1 illustrates application thereof in connection with manufacture of hydrogen fluoride gas. In Fig. 1, 10 indicates in section the gas outlet end of a horizontal cylindrical furnace rotatably mounted on roller supports, one of which appears at 11. A circular opening 12 in the vertical end wall of the furnace affords an outlet thru which gas is discharged from the furnace, it being apparent that the periphery 13 of the outlet is a part of and rotates with the furnace. The main gas conduit 14 is stationary and is held in position by a support 15. Fixed on the end of pipe 14 is flange 17. The adjacent end of a short pipe section 19, constituting a portion of the seal assembly, has fixed thereto a similar flange 20. The two flanges are held together by bolts not shown, and thus pipes 14 and 19 form the stationary gas conduit. While pipe 14 and outlet opening 12 appear coaxial on the drawing, it will be understood that, because of irregularities arising from wear and tear and warping caused by heat, the axis of rotation of furnace 10 is variable, and in operation the axes of opening 12 and pipe 14 are almost always out of alignment which results in a substantially continuous eccentric rotation of periphery 13. Further, wear and tear on roller 11 and the associated track causes the furnace to have a small but appreciable axial movement relative to the fixed pipe 14. Both of these movements contribute to gas leakage at the connection between the furnace and the pipe. In accordance with this invention the foregoing difficulties are overcome by provision of a joint constructed so as to permit relative eccentric and/or axial movement between the furnace and the outlet pipe, and at the same time prevent escape of gas if the furnace is operated under positive pressure or to prevent the ingress of air if the system is operated under negative pressure.

Fixed in gas-tight relation on the end wall of the furnace, as by welding, is a bearing ring

22, having a machined sealing face 23 of substantial radial dimension, which rotates with the furnace. A wear ring 25 having a machined surface 26 provides a second sealing face which contacts with face 23 of bearing ring 22 to form a seal between the fixed and rotating parts of the apparatus. While snugly fitted to the outside of pipe section 19, the inner periphery of wear ring 25 is not fixed thereto but is mounted so as to permit axial movement relative to the fixed gas outlet conduit. Ring 25 is preferably provided with one or more ducts 29 by means of which the contacting faces of rings 22 and 25 may be lubricated.

It will be noted from the drawing that the inner peripheries of bearing ring 22 and of the opening 12 in the end wall of the furnace are substantially spaced apart radially from the adjacent outer periphery of pipe section 19 which projects into the furnace. This construction permits substantial eccentric and/or axial movement of the furnace without causing a metal-to-metal contact between the furnace end wall and its attached bearing ring 22, and the fixed pipe 19. Thus, the annular space between the periphery 13 of furnace wall opening 12 and bearing ring 22 on the one hand, and the outer surface of the inner end of pipe 19 on the other, form an annular port of substantial dimension thru which gas tends to egress from or ingress to the furnace. Assuming operation of the furnace under positive pressure, gas tends to escape from this annular port along radially contacting faces of rings 22 and 25 and also between the movably associated inner periphery of ring 25 and the contiguous outer periphery of pipe section 19. To prevent gas escape by the latter route, ring 25 is recessed to receive an annular ring of packing 30 which may be made of any suitable material such as graphited asbestos, braided copper and lead wool. The packing is held in place by an annular disk 32 shown in section in Fig. 1 and in elevation in Fig. 2, which disk may be connected to wear ring 25 by means of bolts 34. Disk 32 may be mounted on wear ring 25 so as to resiliently hold packing 30 in place.

Flange 20 is provided with a series of threaded holes adapted to receive correspondingly threaded enlarged portions 36 of follower bolts 37. As shown in Fig. 1, the inner end of a bolt 37 projects into a follower bolt seat hole 39 drilled into the outer face of wear ring 25. Mounted on each bolt is a spring 41, one end of which is seated against one face of enlarged threaded portion 36, and the opposite end bearing against the outer face of wear ring 25. The outer end of a bolt 37 projects thru an opening 42 in flange 17 and is provided with a squared head 45 by means of which the position of threaded enlarged portion 36 of bolt 37 may be adjusted axially with respect to flange 20.

In operation, follower bolts 37 are adjusted to move, thru the compressive action of springs 41, the wear ring 25 far enough toward bearing ring 22 so as to form a fluid-tight seal between the sealing faces 23 and 26. It will be noted that the springs act directly on wear ring 25 to hold the contiguous faces of rings 22 and 25 in sealing relation. None of the spring pressure needed to effect this action is transmitted thru or otherwise affects packing 30, the latter material being held in place by the independent clamping ring 32. Since the adjacent faces of rings 22 and 25 are of substantial radial dimension, springs 41 function to adequately maintain

the sealing relation even though bearing ring 22 may be subjected to substantial eccentric and/or axial movement. Since the spring pressure needed to hold ring 25 against ring 22 is not transmitted thru packing 30, the packing is not subjected to any unequal lateral pressures because stress caused by position variations of component parts due to axial or eccentric motion are relieved by the springs. Packing pressure, effected by ring 32, is independent of spring pressure and the packing is subjected only to normal wear incurred by axial motion over the outer surface of pipe section 19. The spring follower bolts 37 permit the wear ring 25 to be axially but not rotatably movable with respect to the fixed pipe 19, and the diameters of follower bolt seat holes 39 are adequate to prevent binding during eccentric motion of the furnace.

The invention is subject to several modifications. While in the apparatus as shown, bearing ring 22 is fixed directly to the furnace wall, it will be understood that the furnace might be provided with a short outlet pipe which is fixed to and rotates with the furnace, in which case bearing ring 22 may be fixedly mounted on the periphery of the outer end of such outlet pipe. Further, in Fig. 1 the relationship of the operative parts may be reversed, that is, the apparatus represented by furnace wall 10 and the attached bearing ring 22 may be fixed, while the conduit formed by pipe sections 14 and 19, the flanges 17 and 20, wear ring 25 and the associated parts may be rotary. The conduit formed by pipe sections 14 and 19 may be used to feed solid material into a rotary chamber in which a gas-forming reaction is taking place. The invention may be adapted to prevent gas leakage at the connection between the reaction chamber and an associated rotary element. For example, the furnace 10 of the drawing may be a fixed reaction chamber and the pipe sections 14 and 19 of Fig. 1 may be replaced by a solid shaft such as the rotary shaft of an agitator. In this situation, flanges 17 and 20, wear ring 25 and the associated parts rotate with the shaft, the sealing off of any tendency for gas to escape from the inside of the fixed reaction chamber being as previously described.

We claim:

1. A joint construction assembly comprising a pair of adjacent members associated and arranged in substantially spaced-apart and in non-fluid-tight relation and to provide a port thru which fluid may egress or ingress, at least one of said members being rotatable with respect to the other; a bearing ring fixed to and projecting from the outside of one of said members, encircling but spaced substantially from said other member to constitute a portion of the wall of said port, and forming by its outwardly directed surface a first sealing face; a wear ring, snugly associated with, projecting outwardly from, carried by but axially movable with respect to said other member and forming by a surface thereof a second sealing face directed toward and adapted to contact said first sealing face in fluid-tight relation; packing movable with said wear ring and mounted immediately between said wear ring and said other member for preventing passage of fluid between said wear ring and said other member, adjustable compression means carried by said other member and arranged externally of both of said members, said compression means acting directly on said wear ring to maintain said sealing faces in fluid-tight relation, said faces being

constructed and arranged to form a seal surrounding said port and to permit substantial eccentric movement of said members without breaking contact between said sealing faces; said members, said rings and said adjustable compression means being so constructed and arranged as to facilitate ready adjustment of said compression means from without said assembly in its entirety.

2. A joint construction assembly comprising a pair of adjacent members associated and arranged in substantially spaced-apart and in non-fluid-tight relation and to provide a port thru which fluid may egress or ingress, at least one of said members being rotatable with respect to the other; a bearing ring fixed to and projecting from the outside of one of said members, encircling but spaced substantially from said other member to constitute a portion of the wall of said port, and forming by its outwardly directed surface a first sealing face; a wear ring, snugly associated with, projecting outwardly from, carried by but axially movable with respect to said other member and forming by a surface thereof a second sealing face directed toward and adapted to contact said first sealing face in fluid-tight relation, packing mounted to prevent passage of fluid between said wear ring and said other member, adjustable thrust means carried by said other member and arranged externally of both of said members, said thrust means acting on the wear ring to maintain said sealing faces in fluid-tight relation, said faces being constructed and arranged to form a seal surrounding said port and to permit substantial eccentric movement of said members without breaking contact between said sealing faces; said members, said rings and said adjustable compression means being so constructed and arranged as to facilitate ready adjustment of said compression means from without said assembly in its entirety.

3. A joint construction assembly comprising a pair of adjacent members associated and arranged in substantially spaced-apart and in non-fluid-tight relation and to provide a port thru which fluid may egress or ingress, at least one of said members being rotatable with respect to the other; a bearing ring fixed to and projecting from the outside of one of said members, encircling but spaced substantially from said other member to constitute a portion of the wall of said

port, and forming by its outwardly directed surface a first sealing face; a wear ring, snugly associated with, projecting outwardly from, carried by but axially movable with respect to said other member and forming by a surface thereof a second sealing face directed toward and adapted to contact said first sealing face in fluid-tight relation, packing movable with said wear ring and mounted immediately between said wear ring and said other member for preventing passage of fluid between said wear ring and said other member, a flange fixed to and projecting outwardly from said other member, adjustable compression means carried by said flange, said compression means comprising a plurality of bolts each threadedly connected to said flange, a spring carried by and movable by each bolt to compressively abut the wear ring, and means to adjust each of said bolts axially of said flange to vary the compression of each of said springs; said compression means being arranged externally of both of said members and acting directly on said wear ring to maintain said sealing faces in fluid-tight relation, said faces being constructed and arranged to form a seal surrounding said port and to permit substantial eccentric movement of said members without breaking contact between said sealing faces; said members, said rings, said flange and said adjustable compression means being so constructed and arranged as to facilitate ready adjustment of said compression means from without said assembly in its entirety.
